(57) **CLAIM**

The ornamental design for a stent, as shown and described.

DESCRIPTION

FIG. 1 is a top front perspective view of a first embodiment
of a Stent showing our new design;

FIG. 2 is a bottom rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a top front perspective view of a second embodiment
of a Stent showing our new design;

FIG. 10 is a bottom rear perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof;

FIG. 16 is a bottom view thereof;

FIG. 17 is a top front perspective view of a third embodiment
of a Stent showing our new design;

FIG. 18 is a bottom rear perspective view thereof;

FIG. 19 is a front view thereof;

FIG. 20 is a rear view thereof;

FIG. 21 is a right side view thereof;

FIG. 22 is a left side view thereof;

FIG. 23 is a top view thereof;

FIG. 24 is a bottom view thereof;

FIG. 25 is a top front perspective view of a fourth embodiment
of a Stent showing our new design;

FIG. 26 is a bottom rear perspective view thereof;

FIG. 27 is a front view thereof;

FIG. 28 is a rear view thereof;

FIG. 29 is a right side view thereof;

FIG. 30 is a left side view thereof;

FIG. 31 is a top view thereof;

FIG. 32 is a bottom view thereof;

FIG. 33 is a top front perspective view of a fifth embodiment
of a Stent showing our new design;

(Continued)

FIG. 34 is a bottom rear perspective view thereof;
FIG. 35 is a front view thereof;
FIG. 36 is a rear view thereof;
FIG. 37 is a right side view thereof;
FIG. 38 is a left side view thereof;
FIG. 39 is a top view thereof;
FIG. 40 is a bottom view thereof;
FIG. 41 is a top front perspective view of a sixth embodiment of a Stent showing our new design;
FIG. 42 is a bottom rear perspective view thereof;
FIG. 43 is a front view thereof;
FIG. 44 is a rear view thereof;
FIG. 45 is a right side view thereof;
FIG. 46 is a left side view thereof;
FIG. 47 is a top view thereof;
FIG. 48 is a bottom view thereof;
FIG. 49 is a top front perspective view of a seventh embodiment of a Stent showing our new design;
FIG. 50 is a bottom rear perspective view thereof;
FIG. 51 is a front view thereof;
FIG. 52 is a rear view thereof;
FIG. 53 is a right side view thereof;
FIG. 54 is a left side view thereof;
FIG. 55 is a top view thereof;
FIG. 56 is a bottom view thereof;
FIG. 57 is a top front perspective view of an eighth embodiment of a Stent showing our new design;
FIG. 58 is a bottom rear perspective view thereof;
FIG. 59 is a front view thereof;
FIG. 60 is a rear view thereof;
FIG. 61 is a right side view thereof;
FIG. 62 is a left side view thereof;
FIG. 63 is a top view thereof;
FIG. 64 is a bottom view thereof;
FIG. 65 is a top front perspective view of a ninth embodiment of a Stent showing our new design;
FIG. 66 is a bottom rear perspective view thereof;
FIG. 67 is a front view thereof;
FIG. 68 is a rear view thereof;
FIG. 69 is a right side view thereof;
FIG. 70 is a left side view thereof;
FIG. 71 is a top view thereof;

FIG. 72 is a bottom view thereof;
FIG. 73 is a top front perspective view of a tenth embodiment of a Stent showing our new design;
FIG. 74 is a bottom rear perspective view thereof;
FIG. 75 is a front view thereof;
FIG. 76 is a rear view thereof;
FIG. 77 is a right side view thereof;
FIG. 78 is a left side view thereof;
FIG. 79 is a top view thereof; and,
FIG. 80 is a bottom view thereof.
